(57)

CLAIM

The ornamental design for a roof rack insert, as shown and described.

DESCRIPTION

FIG. 1 is a perspective view of a roof rack insert;
FIG. 2 is a front elevation view thereof;
FIG. 3 is a rear elevation view thereof;
FIG. 4 is a left elevation view thereof;
FIG. 5 is a right elevation view thereof;
FIG. 6 is a top plan view thereof;
FIG. 7 is a bottom plan view thereof; and,
FIG. 8 is a perspective view of the roof rack insert positioned adjacent to a vehicle roof rack.
The broken lines depict unclaimed environmental subject matter and do not form any part of the claimed design.
